Inventor

C. F. Adams

UNITED STATES PATENT OFFICE.

CLARENCE F. ADAMS, OF DAYTON, OHIO.

GAS CYLINDER VALVE.

Application filed October 26, 1922. Serial No. 597,047.

To all whom it may concern:

Be it known that I, CLARENCE F. ADAMS, a citizen of the United States, residing at Dayton, in the county of Montgomery and 5 State of Ohio, have invented certain new and useful Improvements in Gas Cylinder Valves, of which the following is a specification.

This invention relates in general to valves 10 and more particularly to gas valves used in connection with pressure gas containers.

An object of this invention is to provide an automatic cut-off in charging containers in case of a rupture in any part of charging 15 apparatus which is designed to eliminate loss of gas. In the case of helium, this is an important feature from the standpoint of economy, while with hydrogen the cut-off provides a reliable and quick check to fire, 20 caused by feeding hydrogen or other inflammable gas to a fire caused by some part of the charging apparatus being damaged, such as a safety disc blowing or the charging manifold being ruptured.

25 In case of such an accident, it is practically impossible to reach the charging cylinders and as more gas is being fed to the flame, a further damage is caused. By the provision of the automatic cut-off which is proposed, 30 the possibility of a prolonged fire is eliminated for the reason that at the instant the outside pressure falls below the pressure inside the cylinders, the valves automatically close and prevent further egress of gas.

35 Another object of the present invention is to provide a valve that will retain gas in a container under high pressure without leakage and also to provide a valve which, when on discharge, and especially slow discharge, 40 or when on charge, will not leak around the valve stem.

A further object is to provide a valve that will allow a thoro purging of the cylinder or container without removing the entire 45 valve body therefrom, (a laborious process, involving the use of large wrenches and the efforts of three men), thereby saving time in purging, wear on the valve, and personnel.

50 Another object is to provide a valve affording protection to the valve seat against dirt that ordinarily enters through the discharge nipple when the valve is subjected to operation.

A still further object is to provide a valve

that may be equipped with a fusible safety 55 plug, a safety disc or both plug and disc in combination.

With the foregoing and other objects in view, which shall appear as the description 60 proceeds, the invention resides in the combination of parts and in the details of construction, hereinafter described and claimed, it being understood that various changes 65 may be made, without departing from the spirit of the invention, of the precise embodiment illustrated in the accompanying drawings in which:

Fig. I is a vertical section through the valve assembly.

Fig. II is a vertical section through the 70 safety nipple provided with a safety disc, cartridge plug and retaining nut.

Referring more particularly to the drawings, there is provided a valve casing 1, of suitable material such as brass, exteriorly 75 screw threaded at its upper end to receive a cap 2.

A valve operating means is provided and consists of a rotatable rod 4 having a shoulder 23 adapted to ride between the cap and 80 the washer 3, thus being so clamped as to permit rotation of the rod 4, but prevent its vertical reciprocation. The rod 4 has on its lower end screw-threads 24 to engage corresponding ones in a plug 6. A handwheel 7 85 is fitted around the rod 4 which has screw threads to receive a retaining nut 8. A washer 3¹ is placed between the handwheel 7 and the casing 1 to form a bearing member therebetween.

90 The lower end of the sylphon 5 is sweated or otherwise attached to a shoulder of the plug 6, thus placing the sylphon in such a position that when contracted it will exert a downward pressure on the plug 6. The plug 95 6 is further provided with a cut out portion 26 and inwardly projecting claws 27 below said cut out portion, both being so arranged as to loosely receive and allow a substantial amount of clearance for a nut 12. This nut 100 has a cut out portion.

A cage 9 is screwed into the valve casing 1 near its lower end and is removable when desired. A washer 15 is placed between the lower end of the cage and the shoulder 33 105 of the valve casing. The cage 9 provides a bevelled valve seat 32 for the valve 10. Apertures 13 are arranged in the cage 9 to

register with the passage through the nipple 17. A passage 29 is also arranged in the upper wall 31 of the cage 9.

The valve 10 is provided with a stem 28 which passes through the wall 31 and is screwed into the nut 12 and held against rotation therein by means of a coil spring 11 encircling the valve stem 28, and embedded at its one end in the nut 12 and attached at its other end to the upper wall 31 of the cage 9.

The safety nipple 16 is provided with a communicating passage 34 leading to the passage in the nipple 30. Nipple 16 is threaded both interiorly and exteriorly. It is threaded interiorly to receive a plug 19 having a cartridge 18 and safety disc 20, packing material 21 and a special retaining nut 22 to keep the safety plug assembly in firm contact with the safety nipple 16.

The claw plug 6 may be set in such position as to push or pull on the valve stem nut 12 or may be set in neutral or inoperative position in which case the nut 12 which is attached to the valve stem 28 to act automatically in closing or opening the valve port leading to the gas container through the nipple 30. The position of the plug 6 is regulated by rotating the handwheel 7, transmitting through its stem 4 a reciprocating motion, only, to the plug 6. The plug 6 is prevented from rotating by virtue of being soldered or sweated to the lower end of the sylphon tube 5.

The tension of the spring 11 is just sufficient to carry the weight of the valve 10 complete with its stem and nut 12. Spring 11 also acts as a flexible lock between the nut 12 and the cage 9 and keeps the valve 10 from rotating.

With the valve assembled and screwed into a gas container, and a source of gas supply through a compressor, connected to the nipple 17, the valve 10 may be operated automatically or manually and positively. By turning the handwheel 7 the plug 6 may be set in a neutral or inoperative position, in which case the valve 10 operates automatically, opening the valve port to the gas container as pressure is applied through the nipple 17 and closing automatically in case pressure is suddenly cut off from nipple 17 or for any reason falls below the internal pressure of the cylinder. In case it is desired to operate the valve 10 manually and positively, the valve may be held down positively by screwing the plug 6 down against the nut 12 and thus push the valve 10 open to the position desired. Leakage of gas around the top of the valve casing is prevented by the sylphon tube 5 which affords a flexible and gas tight joint at all times.

The valve 10 may also be closed manually and positively by pulling the plug 6 up until the claws 27 bear upwardly against the un-

der surface of the nut 12. In this position a considerable amount of tension may be brought to bear on the valve seat 32 and this, together with the internal pressure of the cylinder, causes valve 10 to firmly close the valve port leading to the cylinder through the nipple 30. Cage 9 carries several apertures 13 that register with an annular groove 14 in the valve casing 1. Nipple 17 communicates with this groove.

Cage 9 acts as an expansion chamber in the release of gas from a gas cylinder and affords protection to the valve seat from dirt or other foreign matter that may have a tendency to work through the nipple 17 under service conditions.

Thus it will be seen that there have been provided improvements in gas valves to the extent of arranging for automatic action in cutting off the cylinder from the charging line in case of rupture in the charging line and thereby conserving the supply of gas contained in the cylinder and in case of a fire, due to rupture of the charging line, prevents gas from being fed from the cylinders to the fire during the time that it would ordinarily take an attendant to shut off all of the cylinders in the charging bank by hand under danger of injury.

There is also provided a gas valve which is gas tight and dirt proof and so arranged as to allow for purging and swabbing of the gas cylinder with the necessity of removing the valve casing from the cylinder. The internal parts of the valve may be easily removed and provide sufficient opening through the valve to the cylinder to take care of all purging operations. This feature in itself means a great saving of time and trouble and in many cases the complete destruction of valves which often happens with inexperienced operators.

Having thus described my invention, I claim—

1. In combination, in a valve casing, an inlet port and an outlet port, and a member providing a valve seat therebetween, a valve adapted to seat in said valve seat, a valve control means mounted in and movable longitudinally of said valve casing, resilient and non-rotating means loosely securing said valve control means, manually operable means for moving said valve control means longitudinally of said valve casing to positively open, close or place in a position intermediate of said closing position and said open position in which position the valve will be automatically operated by the relative pressure on the inlet and outlet sides of the valve.

2. In combination, a valve casing with an inlet and an outlet port, a valve cage mounted in said valve casing and provided at its lower end with a valve seat for upwardly closing said valve, a valve plug

mounted in said valve casing and capable of limited longitudinal motion relative thereto, a valve adapted to seat in said valve seat and provided with a valve stem extending upwardly through said valve cage and into a recess in the lower end of said valve plug, a nut loosely mounted in said recess and adapted to engage the upper end of said valve stem, and manual means for moving

5 said valve plug longitudinally of said valve casing to such positions as to positively open or close said valve or to such an intermediate position as to permit the valve to be operated by relative pressures on the inlet

10 and outlet sides of the valve.

3. In combination, a valve casing with an inlet and an outlet port, a valve cage mounted in said valve casing and provided at its lower end with a valve seat for upwardly closing said valve, a valve plug mounted in said valve casing and capable of limited longitudinal motion relative thereto, a valve adapted to seat in said valve seat and provided with a valve stem extending

20 upwardly through said valve cage and into a recess in the lower end of said valve plug, a nut loosely mounted in said recess and adapted to engage the upper end of said valve stem, manual means for moving said valve plug longitudinally of said valve casing to such positions as to positively open or close said valve or to such an intermediate

25 position as to permit the valve to be operated by relative pressures on the inlet and outlet sides of the valve, and a safety valve comprising a frangible disk.

30

35

4. In combination, a valve casing with an inlet and an outlet port, a valve cage mounted in said valve casing and provided at its lower end with a valve seat for upwardly closing said valve, a valve plug mounted in said valve casing and capable of limited longitudinal motion relative thereto, a valve adapted to seat in said valve seat and

40 provided with a valve stem extending upwardly through said valve cage and into a recess in the lower end of said valve plug, a nut loosely, resiliently and non-rotatably mounted in said recess and adapted to engage the upper end of said valve stem, and manual means for moving

45 said valve plug longitudinally of said valve casing to such positions as to positively open or close said valve or to such an intermediate position as to permit the valve to be operated by relative pressures on the inlet and outlet sides of the valve.

50

positions as to positively open or close said valve or to such an intermediate position as to permit the valve to be operated by relative pressures on the inlet and outlet sides of the valve, and means preventing gas leakage around the valve stem of said valve.

5. In combination, a valve casing with an inlet and an outlet port, a valve cage mounted in said valve casing and provided at its lower end with a valve seat for upwardly closing said valve, a valve plug mounted in said valve casing and capable of limited longitudinal motion relative thereto, a valve adapted to seat in said valve seat and provided with a valve stem extending upwardly through said valve cage and into a recess in the lower end of said valve plug, a nut loosely mounted in said recess and adapted to engage the upper end of said valve stem, manual means for moving said valve plug longitudinally of said valve casing to such positions as to positively open or close said valve or to such an intermediate
